UNITED STATES PATENT OFFICE.

ROBERT ALLEN, OF ARBELA, ASSIGNOR OF ONE-HALF TO JOHN L. RICHARDSON, OF TUSCOLA, MICHIGAN.

END-BOARD FASTENING FOR WAGONS.

SPECIFICATION forming part of Letters Patent No. 412,941, dated October 15, 1889.

Application filed July 7, 1888. Serial No. 279,848. (No model.)

To all whom it may concern:

Be it known that I, ROBERT ALLEN, a citizen of the United States, residing at Arbelia, in the county of Tuscola and State of Michigan, have invented a new and useful kind of End-Board Fastenings for the End-Boards of Wagon-Boxes, of which the following is a specification.

My invention relates to improvements in end-board fastenings, consisting of rods, a lever, and cranks, with plates and straps of metal for holding the same in place, for the purpose of quickly and easily fastening and unfastening the end-boards of wagon-boxes; and the objects of my improvements are to provide end-board fastenings by which the end-boards of wagon-boxes can be instantly fastened in their places between the side-boards of the box, and can also be instantly unfastened for removal therefrom. I attain this object by the mechanism shown in the accompanying drawings, in which—

Figure 1 is a view of the cast-metal plates by which the mechanism for fastening and unfastening the end-board is made fast to the end-board, and also of the inner ends of the rods, with the clevises for attaching them to the cranks, and also of the inner end of the lever, with its cranks, for moving or holding the rods fast, and also of frontal projections from the plates for receiving and holding the journal ends of the cranks. Fig. 2 is a full view of an end-board, with its rods and plates, and the mechanism for moving the rods adjusted. Fig. 3 is a partial view of a side-board to a wagon-box, showing the hook fastened thereto for the purpose of catching into the slots or holes in the outer ends of the end-board rods, and also the position of the hooks in niches cut in the outer cleats of the side-boards, so as not to obstruct the grooves which receive the end-boards. Fig. 4 is a view of the outer end of end-board rods made with flattened and widened ends perforated with slots or holes for dropping over the points of the side-board hooks when the end-board is inserted in the side-board grooves and pressed down to its place. Fig. 5 is a view of a side-board hook for catching into the slotted ends of the end-board rods,

and also of the screw and of the hooks for fastening the same firmly to the side-board by screwing it through the same and into the thickened part of an iron strap on the outside of the side-board and opposite the hook. 55 Fig. 6 is a separate view of the lever and its cranks by which the end-board rods are drawn inward toward the middle of the end-board to fasten the end-board, and by which they are moved outward to unfasten it. Fig. 60 7 is a partial view of a side-board with a part of its end cleat removed to show the position of the hook, and also to show the iron strap on the outside of the side-board, with that portion of the strap directly opposite the position of the hook sufficiently thickened to serve as a nut for receiving the screw end of the hook.

Similar letters refer to similar parts throughout the several views.

The two plates A A are screwed or bolted to the end-board H in the middle of and near the top of the same, and consist of two pieces instead of one, in order that the journal ends of the cranks b b may be inserted in their 75 holes or bearings in the projections a a. These plates are of metal, with the projections a a cast entire with the plate, or the projections may be bolted through plate and end-board. The frontal projections a a project far enough 80 in front of the face of the plates to allow the cranks b b to be turned around in their bearings without coming in contact with the face of the plates A A. The cranks b b are cast solid with the lever C, or fixed firmly therein, and 85 are moved by turning the lever C from right to left or from left to right, and when the lever C is moved from its position on the right, as shown in Fig. 2, around to the left, as it appears in Fig. 1, the positions of the ends of 90 the cranks b b, to which the rods D D are attached by means of the clevises e e, are reversed, and the rods D D are moved a distance equal to the distance between the centers of the ends of the cranks to which the 95 rods are attached. The lever C is about three inches in length, and its outer end is curved to admit the finger for the purpose of moving the lever, which moves in a horizontal plane from right to left, or vice versa. The 100

end-board rods D D are attached to the cranks b b by means of the clevises e e, and are necessarily moved endwise by moving the lever C. They are of metal, and their outer ends 5 are flattened and widened horizontally, and holes or slots are cut through the flattened ends, as shown in Figs. 4 and 2, so that they may drop over the points of the hooks f f in Figs. 3, 7, and 5 when the end-board is inserted in its grooves in the side-boards and pressed down to its proper place.

e e are clevises, by means of which the rods D D are fastened to the cranks b b, so as to turn thereon, these clevises e e being bolted 15 through the inner ends of the rods D D, which are squared for that purpose.

f f are side-board hooks for catching into the slots g g in the outer ends of the rods D D, and are secured firmly to the side-boards 20 by being made with a screw end, which passes through the side-board and through the thickened portion of an iron strap J, Fig. 7, on the outside of the side-board.

g g in Figs. 2 and 4 show the slotted end 25 of rods D D for dropping over the hooks f f, which slotted ends are drawn tightly into the bends of the hooks f f by turning the lever C from its position in Fig. 2 half around to the left to its position in Fig. 1.

30 H in Fig. 2 is an end-board with mechanism attached, the outer ends of the rods D D being held in holes through the cleats of the end-board and the inner ends of the rods D D on the cranks b b, which cranks are held by 35 the plates A A and their projections a a.

I in Figs. 3 and 7 shows construction of the ends of the side-boards with the hooks f f firmly fastened therein by means of the thickened parts of the straps J J.

40 J in Fig. 7 shows the iron strap used on the outside of the side-boards, having its part opposite the hooks f f sufficiently thickened to serve as a nut for holding firmly the hooks f f by their screw ends.

45 Operation: Place the lever C in line with the right-hand rod D. This extends the rods. Drop the end-board into its position between the side-boards. The slots in the outer ends of the rods D D now drop over the points of

the hooks f f. Throw the lever around to the 50 left until it comes in contact with the end-board. This movement draws the outer ends of the rods into the bends of the hooks and carries the opposite ends by each other and across the axial line of the lever mechanism 55 in opposite directions. The lever C having now traversed more than one hundred and eighty degrees of a circle, the resistance of the rods, instead of drawing it back in the direction whence it came, draws it firmly against 60 the end-board, and thus it is held fast without the aid of a ratchet or other device, while at the same time, the rods being securely engaged in the hooks f f, the end-board is held immovably in its place until the strain on the rods 65 is relaxed by throwing the lever back.

I do not wish to be understood as claiming the invention of two rods or bolts instead of the single rod formerly used, nor as being the only inventor of a mechanism with eccentric 70 movement operated by a lever for tightening and loosening such rods; but I am not aware that such rods have ever been operated in fastening and unfastening end-gates by attaching their inner ends to a revolving mechanism fastened to the middle of the end-gate that will, when revolved by means of its lever, not only carry the rod ends thus attached by each other to shorten longitudinal extent, but will also admit of their crossing its axial line; 75 nor am I aware that hooks with screw-shanks have ever been used in the side-boards to engage the outer ends of such rods, by means of which screws the proper distance for engaging the rods may be maintained or regulated to meet any change occasioned by wear or warp of the boards.

What I claim as my invention, and desire to secure by Letters Patent, is—

In combination with end-boards and the 90 plates A A, the lever C, with its cranks b b, the slotted rods D D, and the screw-shanked hooks f f.

ROBERT ALLEN.
